PORTABLE POWER-OPERATED VACUUM
CLEANER FOR AN AUTOMOBILE OR SIM-
ILAR ARTICLE

Hajime Ota, Tokyo, Japan, assignor to Fedtro, Inc., a
corporation of New York

Filed Oct. 22, 1965, Ser. No. 87,776

Term of patent 14 years

(Cl. D9—2)

FIG. 1

FIG. 3

FIG. 5

FIG. 4

FIG. 2

FIG. 6

FIG. 1 is a front elevational view of a portable power-operated vacuum cleaner for an automobile or similar article showing my new design;

FIG. 2 is a rear elevational view thereof;

FIG. 3 is a side elevational view thereof taken from the right of FIG. 1;

FIG. 4 is an elevational view of the opposite side thereof;

FIG. 5 is a top plan view thereof; and

FIG. 6 is a bottom plan view thereof.

The electric cord is shown broken away in FIGS. 1-4 to indicate indeterminate length.

I claim:

The ornamental design for a portable power-operated vacuum cleaner for an automobile or similar article, substantially as shown and described.
